HYDRAULIC GENERATOR

Edward W. McDonough, Chicago, Ill., assignor to
Aircraft Specialties, Chicago, Ill.

Application November 27, 1940, Serial No. 367,332

5 Claims. (Cl. 103—161)

This invention relates to hydraulic pumps and in particular to the rotating type of pump for producing very high pressures.

The device of this invention is a rotary hydraulic generator of the piston type which is capable of pumping fluid into a system and maintaining it in the system at very high pressures of the order of three thousand pounds per square inch.

It is an object of this invention to provide a rotary hydraulic generator which is the vital element in a live line system of power transmission capable of doing a variety of work immediately upon demand.

Because of that feature and because of the multiplicity of varied things to be done in the operation of aircraft, requiring an immediate source of power, the device of this invention is particularly adapted for use on airplanes. However, the use of the pump of this invention is in no way restricted to use on airplanes but may be used to very great advantage wherever it is desirable to maintain a live line of power which may be utilized at any instant to perform work.

There are many objects and features of this invention, some of which are inherent to the structure of the device, and all of which can be better understood and appreciated from a description of the apparatus of this invention in connection with the accompanying drawings. In addition to the two sectional views of the pump proper, Figures 1 and 2, several other illustrations of important elements of the live line hydraulic generator of this invention have been shown in detail so as to supplement the two principal views and completely disclose to those in this art the construction and features of the hydraulic generator of this invention.

Figure 1 is a sectional view in elevation through the center of the pump.

Figure 2 is a sectional view in elevation through the pump along the line 2—2 in Figure 1.

Figure 3 is a sectional view in elevation through one side of the pump along the line 3—3 in Figure 1.

Figure 4 is a horizontal sectional view through another side of the pump along the line 4—4 in Figure 1.

Figure 5 is a sectional view in elevation through another side of the pump along the line 5—5 in Figure 1.

Figure 6 is a vertical sectional view through any one of the cylinders of the pump showing the piston in full stroke position.

Figure 7 shows the three separated elements of the rotary cam mechanism.

Figure 8 shows the same three elements of the cam mechanism assembled together and in their relative positions with respect to each other when the lead piston is in full stroke position.

The pump is assembled in a housing 10 which remains stationary after the pump is aligned and fastened to a motor by coupling or axle 11. The pump is supported inside housing 10 by pressure bearing 12, and ball bearings 13 and 14 on the suction side of the pump. Bearing 15 as part of a thrust bearing only indirectly supports the elements associated along the horizontal center line of the pump. Suitable and necessary fittings and packing to seal the fluid within the system and at the same time allow the pump to rotate freely are shown though not described here in detail.

The pump of this invention may have any number of cylinders in single or multiple rows. In the drawings a five cylinder rotary pump is illustrated. An inclosed cylinder 16 and a sectional view of cylinder 18 are shown in Figure 1, while cylinders 16, 17, 18, 19 and 20 are shown in sectional views in Figure 2. The cylinders are strengthened in their angular relations to each other by webbing 21 shown only in Figure 1.

The piston 22 is illustrated in minimum stroke position within chamber 23. Valve head 24 has closed off port 25 under the action of coil spring 26 pushing down from cylinder head 27. Piston 22 is actuated through connecting rod 28 by crank pin 29 and as illustrated has closed port 30. It will be observed that all of the pistons are shown in Figure 2 in the same position as piston 22 in cylinder 18, which represents the rotary pump in minimum stroke position.

Cap 31 is screwed over sleeve 32 against the force of springs 33 which are compressed between the collar 34 of thrust bearing 15 and the bearing base 35 of roller bearing 36. Collar 34 is securely fastened to cylinder 37 which reciprocates and rotates within definite limits under the pressure of springs 33 and the fluid pressure built up in the pump. The entire thrust bearing between collar 34 of bearing 15 and the base 35 of bearing 36 is free to rotate, if necessary.

Cylinder 37 has a rod-like portion 38 which extends into the pump and holds pin 39. The purpose of narrowing the cylinder to rod-like proportions is to allow for its extension through the other two elements of the helical cam within the pump. The arrangements of the elements comprising the helical cam and how it functions can be best visualized by studying Figures 7 and 8.

In Figure 7 the elements or parts of the helical cam are shown separated whereas in Figure 8 they are illustrated in associated relation to each other as they would be when crank pin 29 would have moved the master connecting rod 28 and piston 22 into full stroke position, as exemplified by position of piston, valve and crank pin in Figure 6. The relative positions of the parts of the helical cam shown assembled in Figure 1 are as they

would be when crank pin 28 would have moved the master connecting rod 28 and piston 22 into minimum stroke position.

In assembling the helical cam, rod 38 is passed into ring 40 which is held stationary to housing 10 by teeth 41. A spiral slot 42 is cut in ring 40 and another spiral slot 43 is cut in sleeve 44. Sleeve 44 is adapted to slide over ring 40 and when rotated so that slots 42 and 43 overlap one another, they do so at right angles. Thus it will be seen that rod 38, ring 40 and sleeve 44 telescope each other, that is to say, ring 40 is stationary whereas rod 38 fits into ring 40 and is rotatable therein, while sleeve 44 fits over ring 40 and is rotatable thereabout. When assembled pin 39 is securely held in hole 45 in rod 38 and extends through slots 42 and 43. Sleeve 44 is closed at one end by head 46 to which crank pin 29 is securely fastened.

Figure 3 is a vertical view of a section of the pump along the line 3—3 of Figure 1 and shows the elliptical chamber 47 formed in the housing 10 which receives fluid for the pump, the several slots 48 for passing the fluid into circular port 49, and passageways 50 for conducting the fluid from circular port 49 to port 30 surrounding the piston chamber 23.

Figure 4 is a horizontal view of a section of the cylinder 18 along the line 4—4 of Figure 1 and shows a section of the piston 22, openings 51 in the wall of the piston chamber 23, circular port 30 which distributes fluid from channel 50 to the several openings 51 around the chamber, and passageway 52 which is a live line of fluid under pressure from the chamber.

Figure 5 is a vertical view of a section of the pump along the line 5—5 of Figure 1 and shows a chamber 53 for holding the fluid under pressure, several openings 54 for passing fluid into circular port 55 and thence to circular port 56, from which port the fluid may be directed through any number of channels 57 to perform work. Any channel not used can be suitably closed by inserting a plug in openings 59 as indicated in Figure 5.

The hydraulic generator of this invention is directly connected by suitable means to a motor and is designed so that the cylinders rotate while the housing remains stationary. Fluid is supplied through openings in the housing to circular ports which supply the several cylinders in rotation. The fluid is sucked into the cylinders and by reason of poppet valves the fluid is discharged from successive rotating cylinders into a circular port. A detailed description of the passage of the fluid through the pump, that is from the suction side to the pressure side and on to the several points of use will help to explain the many features of this live line hydraulic generator.

Fluid is supplied to the pump through the inlet 58 and collects in chamber 47 and overflows through openings 48 into circular port 49. As the cylinders 16, 17, 18, 19 and 20 revolve around axle 11 which is directly connected with a motor the fluid supplied through circular port 49 will flow through passages 50 into port 30 which encircles piston chamber 23. When piston head 22 is retracted within the chamber 23 sufficiently to uncover the openings 51 the fluid will pass from port 30 into chamber 23. On the return stroke piston 22 will seal off openings 51 to port 30 and tend to compress the fluid in chamber 23. As the compression stroke continues the fluid will press against valve 24 and cause the spring 26 to compress. As the valve head 24 recedes it will uncover port 25 which encircles the upper part

of chamber 23. The pressure from the piston 22 will then force the fluid into circular port 25 and thence through passage 52 into chamber 53. Openings 54 allow for the passage of the fluid under pressure into circular port 55, which encircles axle 11 of the rotating pump, and thence into another circular port 56. The fluid under pressure finally fills passages 57 and as the pressure is built up by the pump the fluid is ready to perform work by transmitting its pressure through the several openings 59.

It should be understood that the inventor has only described in detail the various elements of cylinder 18 and the different parts of the pump 15 for supplying and controlling the passage of fluid through that master cylinder of the pump. Likewise the description of the flow of fluid through the pump was confined to the parts of the pump common to all cylinders, and through cylinder 18. 20 All of the other cylinders will have the same elements and detail of construction, also the fluid will travel identically as described through each and all of the cylinders of the pump. However, the foregoing description of the various elements 25 of the pump and the flow of fluid through the pump should not be understood as describing a static condition, where the fluid flows under the influence of gravity. It should be recalled at this point that the hydraulic generator of this 30 invention has been designed for direct connection to high speed motors to produce pressures all the way up to three thousand pounds per square inch, and more.

As the generator rotates at high speed a dynamic condition exists that is utilized by the 35 inventor in at least two beneficial ways. In the first place the centrifugal influence will supercharge the piston chambers with fluid and thereby increase the efficiency of the pump. In the second place the cranking torque, which is always 40 tending to force the master piston into zero stroke position, increases as the pump builds up pressure, so that there is a constantly increasing dynamic tendency to overcome the resistance of springs 33, and when it does, the piston is forced into zero stroke position.

Attention is called here again to details of construction of this apparatus which make it possible to use it at such high speeds. Figure 3 shows in detail the induction port which encircles the central shaft of the pump, and the elliptical chamber 51. This port is on the suction side of the pump and is designed so as to feed all of the cylinders simultaneously, intermittently or in any order desired. Figure 4 illustrates an induction port which encircles the piston chamber and very efficiently fills the chamber in minimum time through any number of openings 51. Figure 5 shows in detail the outlet port on the pressure side of the pump which encircles the central shaft of the pump and chamber 53 which is disposed in the center of part of said shaft. By virtue of the construction of those elements the inventor may supply fluid to all of the cylinders 55 of the generator simultaneously, intermittently, or in any order desired, as stated. He may likewise utilize the pump pressure through any number of outlets 59 simultaneously, intermittently, or in any order desired, after the desired operating pressure has been once attained.

There is illustrated in the drawings a generally used type of piston, connecting rod and crankpin. It is also within the scope of this invention to use only a crank, instead of the connecting rod and crank pin, to transmit the dynamic pres-

sure being built up through the helical cam to compress springs 33. As the pressure against piston 22 builds up sufficiently the crank rotates pin 29 and at the same time sleeve 44. As sleeve 44 rotates the helical slots 43 guides pin 39 into a helical rotation through ninety degrees, and helical slot 42 in ring 40 guides pin 39 through another ninety degrees of rotating. This rotation and movement of pin 39 is identical with that of cylinder 37 which in turn compresses springs 33 until the piston 22 is in zero stroke position as illustrated in Figures 1 and 2.

As pressure at the numerous outlets of the live line system is used the pressure on piston 22 is lessened and the pressure transmitted through the helical cam against springs 33 falls off. At a certain point the springs 33 will overcome the pressure against it and will move cylinder 37 forward and in doing so pin 39 will helically rotate through slot 42 in ring 40. Then pin 39 will rotate sleeve 44 and pin 29 as it continues to helically rotate in slot 43. Thus the piston 22 is returned again to full stroke position as illustrated in Figure 6 and the cycle of operations is repeated as described as long as the pump is required to keep up pressure in the live line 52 and the system beyond.

Once the generator has built up the pressure desired and there is no work to spend it on the generator continues to rotate but stops pumping. This is a tremendous advantage in pumps because it avoids wearing out the vital elements of the pump, such as the lapped cylinders, pistons and ports. The motor or cylinders revolve on their bearings but there is no circulation of fluid. At such times the pump is standing by for a live line noncirculating system of pressure. The instant the pressure falls the cylinders, which have been rotating idly by reason of their direct connection to a motor not shown, will start to generate pressure for the live line system. Thus it will be seen that the generator of the invention is in effect a variable displacement pump which has tremendous advantages over any constant displacement pump. The latter type of pump, exemplified by the vane or gear types, keeps circulating fluid constantly and wasting energy when in use, while the amount of pumping performed by the generator of this invention varies with the amount of pressure to be made up after some has been used to perform work. The balance of the time the cylinders rotate idly, use little or no energy and pump no fluid.

There are many changes and modifications of the apparatus of this invention which have not been described but which do come within the scope of this invention. For instance, instead of screwing cap 31 to compress springs 33 a bolt could be screwed into cylinder 37 and by suitable construction compress springs 33 against collar 34. Thus instead of cap 31 pulling against teeth on sleeve 32, we would eliminate the cap and have a threaded bolt pull against the threaded inside wall of cylinder 37.

Any of the usual types of pumping fluids may be used in the rotary hydraulic generator described, such as water, thin oils, refined cylinder oils, etc.

The hydraulic generator of this invention would have numerous applications and uses. It would be ideal for use on airplanes to operate

ailerons, flaps, raise the lower landing gear, move machine guns, open and close discharge chutes, doors, etc. It could be used on military tanks for hydraulically moving heavy armament, machine guns and turrets. It could be used wherever a live line noncirculating pressure system within the limits of the generator is desirable and there is a motor available to which the hydraulic generator can be connected.

Having described my invention, what I claim is:

1. A hydraulic generator comprising a stationary housing, a rotating group of cylinders connected directly to a rotating means, each cylinder containing a piston chamber, a piston and poppet valve, each piston chamber being surrounded by two separate ports, each piston being joined by a connecting rod to a common crank pin, and a helical cam mechanism for moving said common crank pin eccentrically so as to alter the strokes of each piston.

2. A hydraulic generator consisting of a stationary housing, a rotor connected to rotating means, a helical cam mechanism actuated by a heavy spring which is regulated by movement of a cap over a sleeve formed by part of said housing, said rotor comprising a plurality of radial cylinders, each cylinder enclosing a chamber, separate circular ports around different sections of each chamber, a slideable piston, and a connecting rod, suitable passageways for transferring fluid to each chamber through the circular ports nearest the crank pin, and suitable passageways for conducting fluid from each chamber through the circular ports farthest from the crank pin to a common pressure chamber for distribution.

3. A rotary hydraulic generator of the class described comprising a housing, a rotor consisting of several cylinders, a piston chamber and piston in each cylinder, all pistons connected to a common crank, said crank connected to a helical cam mechanism consisting of a rotatable sleeve, a fixed ring, and a rotatable and translatable rod, with a pin fixed therein at the end near the center of said rotor, said sleeve and said ring having overlapping slots to accommodate said pin.

4. An hydraulic generator of the class described having a housing for the rotor comprising a plurality of cylinders each containing a piston and piston chamber, each piston connected to a common crank, said crank secured to an axial cam, said cam consisting of a slideable and rotatable sleeve, a fixed ring, and a slideable and rotatable rod having a pin fixed therein at the end near the crank, and said sleeve and said fixed ring having overlapping slots for the passage therethrough of said pin.

5. An hydraulic generator of the class described having a housing for the rotor comprising a plurality of cylinders each containing a piston and piston chamber, each piston connected to a common crank, said crank secured to an axial cam mechanism consisting of a slideable and at the same time rotatable sleeve, a fixed ring, and a slideable and at the same time rotatable rod, said rod having a pin in the end near the crank, said sleeve and said ring having helical slots adapted to permit the passage of said pin simultaneously therethrough.

EDWARD W. McDONOUGH.
